UNITED STATES PATENT OFFICE.

ANTON ALBERTSON, OF MINOT, NORTH DAKOTA.

FLANGE-OILER.

1,154,156.

Specification of Letters Patent. Patented Sept. 21, 1915.

Application filed March 6, 1915. Serial No. 12,643.

To all whom it may concern:

Be it known that I, ANTON ALBERTSON, a citizen of the United States of America, residing at Minot, in the county of Ward and State of North Dakota, have invented certain new and useful Improvements in Flange-Oilers, of which the following is a specification, reference being had thereto to the accompanying drawing.

This invention relates to a flange oiler and is an improvement upon my previous patent granted December 22, 1914, bearing Number 1,122,228.

The principal object of this invention is the production of a simple and efficient mechanism for a flange oiler whereby the lubricant may be directed against the flange of the wheel which is adapted to be brought into direct contact with the sides of the tread of the rails.

Another object of this invention is the production of a simple and efficient means for holding the lubricant feed pipe in a set position.

With these and other objects in view this invention consists of certain novel combinations, constructions, and arrangements of parts as will be hereinafter fully described and claimed.

In the accompanying drawing, Figure 1 is a side elevation of a locomotive showing the flange oiler attached thereto. Fig. 2 is a front elevation of the flange oiler showing the manner in which the feed pipe engages the flange of the wheel. Fig. 3 is a vertical section through a portion of the feed pipe of the flange oiler. Fig. 4 is an enlarged sectional view of the supporting elbow of the feed pipe showing the manner in which the lock nut holds the elbow against accidental swinging movement.

By referring to the drawing it will be seen that 1 designates the lubricant receptacle similar in construction to my previous patent above mentioned, and this receptacle 1 carries a feed pipe 2 upon the lower end of which is threaded an elbow 3. The feed pipe 2 of the receptacle 1 is provided with a depending threaded neck 4 and a lock nut 5 is threaded upon this neck 4 and is adapted to be adjusted thereon to be brought into and out of engagement with the upper edge of the elbow 3.

A lubricant feeding pipe 6 is threaded in the lower end of the elbow 3, and this feed-

ing pipe 6 carries a suitable sleeve 7 as clearly illustrated in Fig. 4 of the drawing. This sleeve 7 may be formed of rubber or other flexible material as indicated by the numeral 8 in Fig. 3, and is provided with a beveled lower edge 9 for the purpose of efficiently engaging the outer face of the flange 10 of the wheel 11. It should be understood that this sleeve 7 is slidably mounted upon the feeding pipe 6 so as to permit the lower end of the sleeve 7 to at all times remain in engagement with the flange 10 of the wheel as the body of the locomotive swings laterally upon the supporting trucks thereof.

The receptacle 1 is supported upon the frame of the locomotive 12 as clearly illustrated in Fig. 1 of the drawing and projects from the side thereof so as to permit the feed pipe 6 to extend direct against the outer face of the flange 10 of the wheel at an angle of approximately forty-five degrees as clearly illustrated in Fig. 2 of the drawing. It, of course, should be understood that it often becomes necessary to remove the feed pipe out of engagement with the flange of the wheel, and for this purpose the lock nut 5 has been provided, whereby the lock nut may be drawn or unthreaded out of engagement with the upper edge of the elbow 3 and permit the entire feeding pipe 6 to be swung out of engagement with the flange 10 of the wheel. When, however, it is desired to retain the pipe 6 in its correct position at substantially an angle of forty-five degrees to the flange of the wheel, the nut 5 is threaded in binding engagement with the upper edge of the elbow 3, and thereby hold the feeding pipe 6 at its proper angle for distributing the lubricant to the flange of the wheel.

From the foregoing description it will be seen that a very simple and efficient means has been produced for retaining the feed pipe at a proper set position to hold the feed pipe in this position against accidental displacement of the swinging movement.

Having thus described the invention what is claimed as new, is:—

A device of the class described comprising a lubricant containing tank, a pipe for feeding lubricant from said tank, a distributing pipe, an elbow threaded upon said feeding pipe, a nut threaded upon said pipe and adapted to be brought into binding engagement with the upper edge of said elbow for

locking said elbow in a set position relative to said feeding pipe, said distributing pipe being secured to said elbow, a self-adjusting sleeve slidably mounted upon said distributing pipe and adapted to engage the flange of a wheel of a locomotive, and said adjusting nut adapted to hold said distributing pipe in a position for discharging lubricant direct against the outer face of the flange of

the wheel at an angle of approximately 10 forty-five degrees.

In testimony whereof I hereunto affix my signature in presence of two witnesses.

ANTON ALBERTSON.
